UNITED STATES PATENT OFFICE.

B. M. DOOR, OF KEWANEE, ILLINOIS.

METHOD OF OPENING AND CLOSING FARM-GATES.

Specification of Letters Patent No. 24,619, dated July 5, 1859.

To all whom it may concern:

Be it known that I, B. M. DORR, of Kewanee, in the county of Henry and State of Illinois, have invented a new and useful

5 Improvement in Farm-Gates; and I do hereby declare that the following is a full, clear, and exact description of the same, reference being had to the accompanying drawings, making a part of this specification, in 10 which—

Figure 1 represents a front elevation of my invention, partly in section. Fig. 2 is a plan or top view of ditto.

Similar letters of reference in both figures 15 indicate corresponding parts.

This invention relates to an improvement in the mechanism by which approaching vehicles open and close gates; and the invention consists in arranging under the gate 20 a pinion which engages with two racks on opposite sides, said racks to be connected, by means of suitable levers and rods, with the two panels of a sliding gate, so that by giving the pinion an oscillating motion, the two 25 panels slide to or from each other in opposite directions, and that by connecting said pinion, in the proper places, with crank levers the gate is opened or closed as the wheels of a vehicle pass over them.

30 To enable those skilled in the art to make and use my invention I will proceed to describe its construction and operation.

The two panels, A A', of the gate slide on a rod, a, which is attached to the upper 35 side of the beam, B. This beam is put into the ground so as to be flush with it and attached to it a short distance from its center, and at right angles with the same is another beam C. The lower edges of the panels, A 40 A', are guided by means of loops, b, which embrace the rod, a, and the upper edge is guided in grooved lugs, c, which are secured to standards, D D', attached to the upper side of the beam, B. Both panels of the 45 gate are operated by levers, d d', which are fulcrated on the inner side of the standards, D D', and the longer end of which connects with the front stiles, e e', of the two panels by means of rods, f f'. The short ends of 50 these levers, which extend down into a cavity, g g', cut into the upper side of the beam, B, connect with toothed racks, h h', which slide in suitable guides in the cavities, g g', and these racks engage with a pinion, i, from 55 which two arms, j j', extend on opposite sides, which connect, by means of rods, k k', with the crank levers, E E'. These levers

are attached to the upper side of the rectangular beam, C, turning easy in the staples, l, and at such a distance from the gate that the wheels of a vehicle pass over the same before the draught animals have reached the gate. Weights, m, are secured to the crank levers in such a manner that the same, when left to themselves, assume a vertical position, and the ends of the rods, k k', are slotted so that the same do not interfere with the free action of the crank levers, and that the latter, after the gate has been opened or closed, are always free to place themselves in a vertical position.

The operation is as follows:—When a vehicle drives up to the gate in the direction indicated by arrow 1, and as soon as one of the wheels strikes the crank lever, E', it turns down in the same direction, and by the action of the rod, k', the pinion, i, is turned in the direction of arrow 2, causing the racks, h h', to move in the direction of arrows 3 3'. By the action of the racks on the short ends of the levers, d d', the long ends, together with the panels, A A', are moved in the direction of arrows, 4 4', and the gate is opened. The slots in the rods, k k', are so long that they allow the crank levers to assume their original vertical position, after the gate is opened and as one of the wheels of the vehicle comes in contact with the crank lever, E, the gate is closed, the several parts being moved in the opposite direction to the arrows placed on them and the crank levers again assume their upright position, so that they are always in the proper position for the wheels of an approaching vehicle.

By placing the gate on rollers its motion may be made easier, and it will be noticed that by the proportion existing between the short and the long end of the levers, d d', a slight motion of the racks, and of the pinion is sufficient to open or to close the gate.

What I claim as new and desire to secure by Letters Patent, is:—

The arrangement of the pinion, i, the toothed racks, h h', and the levers, d d', to operate in combination with the slotted rods, k k', and the crank levers, E E', for the purpose of opening and closing the gate, A A', substantially as herein described.

B. M. DORR.
